DESIGN FOR A COMMUNICATION SWITCH- BOARD

Lloyd J. Andres, Chicago, Ill.

Application June 24, 1940, Serial No. 93,219

Term of patent 7 years

To all whom it may concern:

Be it known that I, Lloyd J. Andres, a citizen of the United States and resident of Chicago, in the county of Cook and State of Illinois, have invented a new, original, and ornamental Design for a Communication Switchboard, of which the following is a specification, reference being had to the accompanying drawings, forming part thereof.

Fig. 1 is a front elevational view of a communication switchboard showing my new design;

Fig. 2 is a top plan view;

Fig. 3 is a side elevational view. The side not shown is the same as Fig. 3.

The rear surface of the switchboard is plain.
I claim:

The ornamental design for a communication switchboard, as shown and described.

LLOYD J. ANDRES.
